UNITED STATES PATENT OFFICE.

WALTER F. RICHARDS, OF QUINCY, ILLINOIS.

DENTAL LATHE-FILE.

1,105,456.

Specification of Letters Patent.

Patented July 28, 1914.

Application filed March 18, 1912. Serial No. 684,649.

To all whom it may concern:

Be it known that I, WALTER F. RICHARDS, a citizen of the United States, resident of Quincy, in the county of Adams and State 5 of Illinois, have made a certain new and useful Invention in Dental Lathe-Files; and I declare the following to be a full, clear, and exact description of the same, such as will enable others skilled in the art to which 10 it appertains to make and use the invention, reference being had to the accompanying drawings, and to letters or figures of reference marked thereon, which form a part of this specification.

15 Figure 1 is a side view of the invention as applied. Fig. 2 is a section on the line 2—2, Fig. 1. Fig. 3 is a top plan view of the file. Fig. 4 is a bottom plan view of the file. Fig. 5 is a section on the line 5—5, 20 Fig. 1. Fig. 6 is a top plan view of another form of the invention. Fig. 7 is a bottom plan view of the same. Fig. 8 is a section on the line 8—8, Fig. 6.

The invention has relation to dental lathe 25 files, having for its object to provide improved means for surfacing and festooning the vulcanite between and about the necks of the teeth in artificial dentures, and it consists in the novel construction and combinations of parts, as hereinafter set forth.

In the accompanying drawings, illustrating 30 the invention, the numeral 1 designates the short flat blade of the file, of general triangular flat or V-form, having a flat smooth top 2 and a flat bottom 3, converging 35 oppositely beveled straight lateral edges 4 terminating in an acute angle point and a rear end tang extension 5.

The bottom surface of the file is file cut 40 straight across from side to side at right angles to the longitudinal axis of the file in a parallel manner, as shown at 6, 6, to provide a series of transverse serrations extending from the heel to the point of the blade.

45 The tang has a beveled edge portion 7 at one side and at the opposite side is provided with an extension 8 the outer edge 9 of which is concave, and beveled at 10. This tang is designed to fit within a beveled-edge groove 50 11 of the slide bar of the lathe, a rounded or cone-end set screw 12 having engagement

with the concave outer edge of said extension, to force the opposite beveled edge portion of the tang against the similarly formed edge wall of the slide groove and hold the 55 file securely against displacement or being shaken loose at the high speed at which it is run in practice.

One form of the invention is shown in Figs. 1—5 of the drawings, wherein the lateral edges of the file are oppositely beveled in a convex manner at 13, said edges having each a series of oblique file teeth 14, terminating short of the wider face of the file as indicated at 4, so that they are thereby rendered safe or non-cutting.

A second form of the invention is shown in Figs. 6, 7 and 8 of the drawings, wherein the lateral edges of the file are oppositely beveled, at 16, the bottom surface of the file 70 being flat from side to side, and the oblique file teeth being omitted. In this form of the invention, the transverse teeth 6, may be sharpened when worn by regrinding the bevel of the edges.

Both forms of the file are capable of being stamped from sheet metal of the same thickness throughout.

The file is of delicate, thin character and is preferably of a length about equal to 80 twice its width, in order that it may be strong and not bend too easily. The inclination given the lateral edges of the file in this way will also provide for proper cutting action of said edges, which run 85 close up to the necks of the artificial teeth. The parallel teeth are designed to act in the manner of a succession of sharp planing edges upon the vulcanite, and are required to be at right angles to the longitudinal 90 axis of the file for this purpose.

The straight lateral edges converge at an angle and are reduced by the bevel thereof to comparative thinness, for working in narrow places of the vulcanite. The oppositely beveled edges form, with the opposite face of the file, a three-sided point, useful in working in corners.

Having thus described my invention, what I claim as new and desire to secure by Letters Patent is:

A dental lathe file, having, a thin flat V-

form blade provided with straight oppositely beveled lateral edges converging at an angle, a flat working face having a series of transverse serrations, a plane back surface, and 5 a three-sided point formed by the beveled lateral edges and the opposite face of the file, said beveled lateral edges being reduced to comparative thinness and said transverse

serrations extending to the extremity of said point.

10

In testimony whereof I affix my signature, in presence of two witnesses.

WALTER F. RICHARDS.

Witnesses:

LYMAN McCARL,

JOHN T. INGHAM.
